UNITED STATES PATENT OFFICE.

EARL J. GIBBS, OF EVANSVILLE, WISCONSIN, ASSIGNOR OF ONE-HALF TO EDWIN S. CARY, OF EVANSVILLE, WISCONSIN.

ELECTRIC-FUSE CUT-OUT.

1,102,579.

Specification of Letters Patent. Patented July 7, 1914.

Application filed January 27, 1913. Serial No. 744,528.

To all whom it may concern:

Be it known that I, EARL J. GIBBS, a citizen of the United States, residing at Evansville, in the county of Rock and State of Wisconsin, have invented certain new and useful Improvements in Electric-Fuse Cut-Outs; and I do declare the following to be a full, clear and exact description of the invention, such as will enable others skilled in the art to which it appertains to make and use the same.

This invention relates to junction boxes, and more especially to those which include thermal cut-outs; and the object of the same is to construct a fuse box capable of containing two fuses for high tension wires, and between them a switch mechanism consisting preferably of a rotatable plate of insulating material, so that when one fuse is burned out said mechanism may be turned to cut out this fuse and to cut in or switch in the other fuse—thereby bringing an insulating plate between the live fuse and the bared ends or terminals of the line wires and the dead fuse which is to be replaced by a new one and which requires the insertion of the operator's hand. This object is carried out in the manner illustrated in the accompanying drawings and described in the following specification and claims.

In said drawings—Figure 1 is a transverse vertical section through the box or casing, and a front elevation of the mechanism comprising one form of my invention; and Figs. 2, 3, and 4 are sections on the lines 2—2, 3—3, and 4—4, respectively, of Fig. 1.

The box or casing B has a hinged door D and is of a size to contain the mechanism hereinbefore described and two ordinary thermal fuses F, herein illustrated as of that type which have bared terminals T at their extremities which in common use are slipped between the arms of forked connectors by means of which the fuses are cut into the line where they are to be employed. When high tension or an overload is thrown onto this line, the fuse burns out, by which is meant that the fuse wire contained within the insulating or fiber shell of the fuse F is melted; hence the current is interrupted and it becomes necessary to replace this fuse with another.

The purpose of the present invention is to permit the operator to throw the switch mechanism from a position outside the box

or casing, so that immediately he cuts out the dead fuse and cuts in a live one, and the resumption of the current is instantaneous—then at leisure he opens the box and replaces the dead fuse without danger to himself.

66

In the construction illustrated on Sheet 1, an insulating shaft 1 is journaled in bearings 2 in the top *t* and bottom *b* of the box B, and one of its ends is extended and carries a knob or handle 3 by which said shaft 35 may be rotated without opening the box door D. The shaft is held in its journals by suitable means such as transverse pins 4 near its extremities, and between the top and bottom of the box the shaft is enlarged into an insulating plate 5 which may be integral with or attached to the shaft, or the shaft may be made in the form of two trunnions or stub-shafts projecting upward and downward from said plate. The vertical dimension or length of this plate is less than the height of the box between its top and bottom for a purpose to appear below, and the lateral dimension or width of this plate is by preference about that of the interior of the box so that when it stands across the same as seen in Fig. 3 the rear half of the box into which lead the line wires W is entirely shut off from the forward half. Therefore the operator may open the door D and remove and replace the fuse F in the front half of the box with perfect safety, because it is impossible to come into contact with any of the live connections within the rear half.

88

One of the line wires W is connected with the base of an upper fork 10, and the other with a lower fork 11, the arms of each of said forks being preferably made of spring metal as usual. On each face of the plate 5 near its upper and lower ends are mounted connectors which are complementary of each other, and each of which has the construction best illustrated in Fig. 2. Each connector is of metal, suitably secured to the plate 5 as at 12, carrying a fork 13 at one extremity within which one terminal, T of the fuse F is slipped as shown, and its body 14 thence led inward toward the transverse center of the plate, then toward the trunnion, and finally carried outward into a blade 15 so disposed that it will pass between the arms of one of the forks 10 or 11. In order to effect this disposition of the blades, the latter must stand above the upper and lower edges of the plate 5, so that when 11

the shaft is turned and the plate changes its position its upper edge swings beneath the upper fork 10 and its lower edge above the lower fork 11, and the blades 15 at one side of said plate pass out of engagement with the line-forks and around to the front side of the plate 5, while the opposite pair of blades 15 pass around into engagement with the line-forks so as to reestablish the circuit. Meanwhile the burnt-out fuse F which formerly stood behind the plate 5 is also brought around in front of it, and can be removed through the door D in a manner already described. Thus it will be seen that by the construction of my invention described the operator is absolutely protected from possibility of electric shock, and extremely unlikely to be injured because his hand is quite remote from the point of danger. I do not wish to be limited to any particular type of fuse, and of course the sizes and proportions of parts are not essential to the successful operation of the invention.

25 25. What is claimed as new is:

1. The combination with a casing, an upright shaft rotatably mounted therein and carrying an insulating plate of a size to fit transversely within said casing, and means for turning the shaft and plate; of a pair of line wires, a pair of forks within the casing connected with said wires, a pair of connectors secured to each face of the plate and adapted to be thrown into connection with the line wire forks by the turning of said plate, and fuses connecting the members of each pair of connectors.

2. The combination with a casing having an open front, an upright shaft rotatably mounted therein and carrying an insulating plate of a size to fit transversely within said casing and whose upper and lower ends are spaced from the top and bottom thereof

respectively, means for turning said shaft and plate, and a pair of fuses; of a pair 45 of line wires led through the rear of the casing, a pair of forks connected with their terminals at points above and below the upper and lower ends of said plate and behind it, and a pair of connectors on each 50 face of said plate, each connector comprising an upright arm having a fork adapted to receive one terminal of the fuse and a horizontal arm standing in a plane beyond the end of said insulating plate and comprising 55 a blade adapted to be turned between the arms of the line wire fork.

3. In a fuse box cut-out, the combination with a box-like casing having a door in its front and journals in its top and bottom, 60 the line wires led through the rear of the box, and terminal members respectively connected with them and carried by the top and bottom of the box; of a plate of insulating material of less length than the internal 65 height of the box and of a width corresponding with the width of the box, trunnions at the centers of its upper and lower ends projecting through said journals, pins through said trunnions holding the plate centered between the top and bottom of the box, a handle on the lower trunnion, a pair of fuses, and for each fuse a pair of connectors of L-shape whereof one arm detachably receives the bared terminal of the fuse and the other arm projects beyond the end of said insulating plate and is adapted to make contact with a wire-terminal, for the purpose set forth.

In testimony whereof I have hereunto set 80 my hand in presence of two subscribing witnesses.

EARL J. GIBBS.
